Howard M. Cohn

(57) **CLAIM**

The ornamental design for a window lock, as shown and described.

DESCRIPTION

FIG. 1 is a perspective view of a window lock showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of the window lock, shown in an open configuration; and,

FIG. 11 is an exploded perspective view of the window lock. The dash-dot broken lines in the drawings depict portions of the window lock that form no part of the claimed design.

1 Claim, 11 Drawing Sheets
